(57) **CLAIM**

The ornamental design for an aroma humidifier, as shown and described.

DESCRIPTION

FIG. 1 is a perspective view of an aroma humidifier showing my new design;

FIG. 2 is a front elevational view thereof;

FIG. 3 is a top elevational view thereof;

FIG. 4 is a left side elevational view thereof;

FIG. 5 is a rear side elevational view thereof;

FIG. 6 is a right plan view thereof; and,

FIG. 7 is a bottom plan view thereof.

The broken lines in the drawings illustrate features that form no part of the claim.
